UNITED STATES PATENT OFFICE

JOSEPH PIKUL, OF TROY, NEW YORK, ASSIGNOR TO THE REECE BUTTON HOLE MACHINE COMPANY, OF BOSTON, MASSACHUSETTS, A CORPORATION OF MAINE

STITCHED BUTTONHOLE

Application filed July 17, 1931. Serial No. 551,397.

This invention relates to stitched buttonholes and it has for its principal object to provide a novel buttonhole which is so constructed that the stitches will have a bight of a less width on one side of the fabric than on the other.

In the stitching of a buttonhole on an ordinary buttonhole sewing machine the penetrating thrusts of the needle are usually made alternately along the line of the buttonhole slit and through the work at a distance back from the slit. In other words, the alternate thrusts of the needle will be along the line of the buttonhole slit while the other thrusts will be through the work at a distance back from the slit. As a result when the loops of thread are concatenated in forming the stitching a portion of each thread loop will appear on both faces of the fabric extending from the slit to a point where the needle pierced the fabric back from the slit, and the width of the stitching, or as it is sometimes referred to, the "bight", is the same on both faces of the fabric.

In the stitching of a buttonhole the stitches are usually so concatenated that the interlocking of the threads appears on the front face of the fabric to form what is known as the "purl," it producing a finished appearance to the face of the buttonhole. On the back side of the fabric, however, the portions of the stitches that are visible present parallel threads or thread portions extending from the slit of the buttonhole back to the points where the needle was thrust through the fabric. This arrangement of threads does not give the finished appearance to the buttonhole on the back of the goods that the purl does on the front of the goods.

It is one of the objects of my present invention to provide an improved stitched buttonhole which is so made that the buttonhole stitches will have a bight of less width on one face of the fabric than on the other

and preferably the bight of lesser width will be on the back face of the fabric.

In carrying out my invention the portions of the loops of thread which pass through the goods back from the buttonhole slit are so arranged that they emerge from the front face of the fabric at a suitable distance back from the slit to permit the formation of the usual purl but on the back face said loops emerge from the goods at a lesser distance from the buttonhole slit with the result that the amount of thread visible on the back face of the fabric is correspondingly reduced thereby improving the appearance of the buttonhole.

In order to give an understanding of the invention I have illustrated in the drawing a selected embodiment thereof which will now be described after which the novel features will be pointed out in the appended claims.

Fig. 1 is a fragmentary perspective and somewhat diagrammatic view greatly enlarged, illustrating a portion of a buttonhole made in accordance with my invention;

Fig. 2 is an enlarged cross section through a piece of goods having a stitched buttonhole embodying my invention;

Fig. 3 is a somewhat diagrammatic view illustrating the front of a buttonhole embodying my invention;

Fig. 4 is a similar view illustrating the back face of said buttonhole;

In the drawing 1 indicates the work in which the buttonhole is formed and 2 is the buttonhole slit. The buttonhole stitch shown in Fig. 1 is formed with two threads indicated at 3 and 4 respectively, and is the type of stitch which would be made with a well-known buttonhole sewing machine which is equipped with a needle operating from above the work and loopers operating beneath the work, one of the loopers being threaded. The thread 3 is the thread carried by the needle while the thread 4 is the looper thread. From

the thread 3 there is formed a plurality of thread loops 5 which extend through the buttonhole slit 2 and also a series of loops 6 which extend through the goods 1 from the back face. The loops 5 and 6 are not only concatenated with each other but also with loops 7 of the looper thread 4.

Each loop 5 of the thread 3 extends through a loop 6 of said thread 3 on the front face of the fabric and each loop 6 extends through a loop 7 of the thread 4 while each loop 7 passes through one of the loops 5 of the thread 3. This manner of interlocking or concatenating the thread brings the interlocking of the threads on the front face of the fabric as shown in Fig. 1 and thus produces the purl effect.

In forming the stitching the needle thrusts which carry the loops 6 through the fabric are so made that the needle will enter the goods 20 on the face 14 at a point 8 which is a lesser distance from the buttonhole slit than the points 9 at which the needle emerges from the face 15 of the goods. With this arrangement the portion 10 of each loop 6 which is 25 located within the body of the work 1 will extend at an angle to the plane of the work.

Of the double thread which constitutes the portion 10 of each stitch one ply or end 11 leads to one loop 5 and the other ply or end 30 12 leads to the next adjacent loop 5. As a result the only thread portions of the buttonhole stitching which are visible on the back face of the goods 1, which is the under side 35 in Figs. 1 and 2, are the portions 13 which extend from the points 8 where the loops 6 enter the back side of the goods to the buttonhole slit.

Since the points 8 at which the needle 40 thrusts enter the face 14 of the fabric are nearer to the buttonhole slit than the points of emergence 9 the width or bight of the stitching appearing on the back face 14 of the fabric will be less than that appearing on the 45 front face 15.

The distance of the points 8 at which the loops 6 enter the face 14 of the work from the buttonhole slit 2 may vary more or less without involving any change in the invention 50 and the nearer these points 8 are to the buttonhole slit the less will be the bight of the stitches on the back face and the less the stitches will be visible.

The drawing shows a construction in which 55 the loop portion 6 of each stitch enters the fabric from the under face 14 very close to the buttonhole slit so that there will be a very slight amount of thread visible on the under face 14 of the goods. In a buttonhole made 60 in this way the front face of the fabric has the same appearance usually found on buttonholes made on a buttonhole sewing machine but at the back face of the goods or fabric a small amount of thread will be visible.

65 Where the buttonhole is made as herein

illustrated the small amount of thread indicated by the portions 13 which appears on the back face of the fabric serves to give a proper finish to the buttonhole in that they cover the edges of the goods at the sides of the buttonhole slit but the amount of thread which is visible on the back face of the fabric is not sufficient to produce an unsightly or unfinished appearance.

I claim.

1. A stitched buttonhole comprising a piece of goods with a buttonhole slit and a series of concatenated thread loops binding the edge of the buttonhole slit, certain of the loops passing through the slit and other loops passing through the work and emerging therefrom on one face thereof at a greater distance from the slit than on the other face thereof, the interlocking of the thread loops being on said first-named face.

2. A stitched buttonhole in which the buttonhole stitches are formed by the concatenating of loops in two threads, the alternate loops of one thread entering one face of the goods adjacent the buttonhole slit and passing through the goods and emerging from the other face at a greater distance from the buttonhole slit than the point of entrance, and the other loops of said thread passing from one face of the fabric to the other through the buttonhole slit and also passing through the first-named loops, the loops of the second thread passing through the loops occupying the slit of the buttonhole and being looped about the other loops of said other thread.

3. A buttonhole stitched with interlocking thread loops wherein the width of the stitching transversely of the buttonhole is wider on one side of the material than on the other and the thread loops are interlocked on that side of the material on which the stitching is widest.

4. A buttonhole stitched with a plurality of threads which are interlocked with each other, a portion of the thread forming each stitch entering the material on one face closely adjacent the buttonhole slit and extending through the material in an inclined direction to the entering face thereof and emerging from the other face at a considerable distance from said slit, the interlocking of the threads occurring on said other face.

5. A stitched buttonhole wherein each stitch is formed with interlocking thread loops, a portion of the thread of each stitch entering one face of the material at a point closely adjacent the buttonhole slit and extending through the material at an angle to said face and emerging from the other face at a considerable distance back from the slit, the interlocking of said loops occurring on said other face.

6. A stitched buttonhole in which a portion of the thread forming each stitch thereof

enters the material on one face thereof at a point so closely adjacent the buttonhole slit that the thread of each stitch is hardly visible on said face and extends through the material in a direction which inclines away from said slit and emerges from the other face of the fabric at a considerable distance back from the slit, the concatenation of the stitching appearing on said other face.

10 In testimony whereof, I have signed my name to this specification.

JOSEPH PIKUL.
